UNITED STATES PATENT OFFICE.

STANISZLAW ARMACZKI, OF NATRONA, PENNSYLVANIA.

BOAT-PROPELLING MECHANISM.

1,139,471.

Specification of Letters Patent. Patented May 18, 1915.

Application filed January 18, 1915. Serial No. 2,849.

To all whom it may concern:

Be it known that I, STANISZLAW ARMACZKI, subject of the Emperor of Russia, residing at Natrona, in the county of Allegheny and State of Pennsylvania, have invented certain new and useful Improvements in Boat-Propelling Mechanism, of which the following is a specification.

This invention relates to certain new and useful improvements in boat propelling mechanism.

The primary object of this invention is to provide oppositely arranged alternately reciprocating foldable pushers upon a boat whereby the boat is given successive forward impulses.

A further object is to provide rearwardly movable pushers at the stern of a boat, the same being operable by a motor within the boat and adapted by successive rearward thrusts to force the boat forward upon its course under the direction of the rudder.

With these general objects in view and others that will appear as the nature of the invention is better understood, the same consists in the novel combination and arrangement of parts hereinafter more fully described, illustrated in the accompanying drawings and set forth in the appended claim.

In the drawings forming a part of this application and in which like designating characters refer to corresponding parts throughout the several views, Figure 1 is a top plan view of a boat provided with the present invention. Fig. 2 is a view of one of the propulsion members or pushers, the blades being shown in their unfolded operative positions and in vertical longitudinal central section. Fig. 3 is a view similar to Fig. 2 but with the blades inoperatively folded as positioned upon the return forward stroke of the pusher. Fig. 4 is a detail perspective view of the hinged end portion of one of the pusher blades, and Fig. 5 is a perspective view of the operating member of one of the pushers detached.

Referring more in detail to the drawings, the present invention is illustrated as installed upon the boat 10 which is provided with a steering rudder 11 centrally positioned upon the boat stern 12.

An operating member 13 of the form illustrated in Fig. 5 and being substantially T-shaped with a shaft 14 and having a cross head 15 thereon, is slidably mounted longi-

tudinally of the boat adjacent each rear corner thereof and with the shafts 14 of such members slidably extending through rectangular bushings 16 which are passed through the boat stern 12, it being noted that the shafts 14 are rectangular in cross section and that the heads 15 are positioned in the same horizontal plane rearwardly of the boat stern and at a point below the normal water level.

Each of the shafts 14 projects inwardly of the boat and extends between spaced guide strips 17 which are provided with longitudinal grooves 18 upon their adjacent faces for the sliding reception of the block 19. The block 19 is secured to the free inner end of the shaft 14 of the operating member by such means as the bolts 20, it being noted that any sliding reciprocatory motion which is imparted to the blocks 19 will move the operating member 13 which is secured thereto.

A motor 21 of any desired form and herein illustrated as a steam engine having oppositely arranged piston cylinders 22 provides the propelling means for the operating members. The reciprocating piston (not shown) of each of the cylinders has a rearwardly extending piston rod 23, while the rear end of each of said rods is hingedly connected as at 24 to the oppositely-arranged blocks 19 of the operating members.

Oppositely arranged foldable blades 25 are hinged as at 26 to the opposite upper and lower sides of the heads 15, which heads are provided with tapered sharpened rear edges 27 positioned between the pair of blades carried thereby when the blades are folded as shown in Fig. 3. The pusher blades 25 are substantially dish-shaped and have their bottoms 28 forwardly positioned and being in a plane substantially parallel with the boat stern when the said blades are operatively open as shown in Fig. 2.

It will thus be seen that when the blades upon the operating member are so operatively positioned as also shown with respect to the left-hand pusher in Fig. 1, a movement of the piston rod of such operating member rearwardly will rearwardly move the operating member, while its blades are open, which will result in exerting a forward impulse to the boat by reason of the rear movement of the pusher through the water beneath the surface of which it is positioned. Upon the return inward reciprocation of the

piston rod and operating member, the latter moving in a direction of the arrow as indicated in Fig. 3, and with respect to the right-hand pusher in Fig. 1, the blades will 5 fold upon the carrying head 15 by means of the hinges 26 and by reason of the pressure of the water during the forward movement of the head and thereby allow a free return movement of the operating member. While 10 the motor and its piston rods are designed for continuous operation, subject to the control of the engineer of the boat, the pushers will be alternately reciprocated and the rudder 11 is designed to maintain the boat upon 15 its desired forward course of travel.

While the form of the invention herein shown and described is what is believed to be the preferred embodiment thereof, it is nevertheless to be understood that minor 20 changes may be made without departing from the spirit and scope of the invention as claimed.

What I claim as new is:—

A device of the class described comprising 25 in combination with a boat having the

stern thereof provided with opposite perforations therethrough, pusher members having operating shafts slidably mounted through the said perforations and having rearwardly arranged cross heads with tapered rear edges and arranged in the same horizontal plane, dish shaped blades opening rearwardly and hinged to the upper and lower sides of the said heads, spaced strips positioned within said boat at opposite sides of the lines of movement of the said shafts and provided with guide ways on their adjacent faces, slide blocks movably positioned within the said guide grooves, and secured to the inner ends of the said 35 shafts, and alternating reciprocating power means operatively connected to the said blocks.

In testimony whereof I affix my signature in presence of two witnesses.

STANISZLAW ARMACZKI.
